Primary Examiner — Carol P Rademaker(74) *Attorney, Agent, or Firm* — Leydig, Voit & Mayer, Ltd.(57) **CLAIM**

The ornamental design for a bottle with cap, as shown and described.

DESCRIPTION

FIG. 1 is a top, front, left side perspective view of a first embodiment of a bottle with cap of the new design;

FIG. 2 is a top plan view thereof;

FIG. 3 is a bottom plan view thereof;

FIG. 4 is a front elevational view thereof;

FIG. 5 is a back elevational view thereof;

FIG. 6 is a right side front elevational view thereof;

FIG. 7 is a left side elevational view thereof;

FIG. 8 is a top, front, left side perspective view of a second embodiment of a bottle with cap of the new design

FIG. 9 is a top plan view thereof;

FIG. 10 is a bottom plan view thereof;

FIG. 11 is a front elevational view thereof;

FIG. 12 is a back elevational view thereof;

FIG. 13 is a right side front elevational view thereof; and,

FIG. 14 is a left side elevational view thereof.

The broken lines in the views depict environmental structure that is shown for illustrative purposes only and that does not form any part of the claimed design.
